ATTORNEY

UNITED STATES PATENT OFFICE.

ORA A. COLBY, OF LARIMER, PENNSYLVANIA, ASSIGNOR TO WESTINGHOUSE ELECTRIC & MANUFACTURING COMPANY, A CORPORATION OF PENNSYLVANIA.

THERMAL RELAY.

Application filed December 31, 1918. Serial No. 289,093.

To all whom it may concern:

Be it known that I, ORA A. COLBY, a citizen of the United States, and a resident of Larimer, in the county of Allegheny and 5 State of Pennsylvania, have invented a new and useful Improvement in Thermal Relays, of which the following is a specification.

My invention relates to relays and particularly to thermal relays.

The object of my invention is to provide a thermal relay that shall have a plurality of contact devices which are adapted to be adjustable with respect to each other.

15 In practicing my invention, I provide a main movable member, a single bimetallic spring for actuating the same, a heater for the bimetallic spring, a plurality of resiliently-mounted contact members on the main movable member and adjustable stationary contact members. The adjustable stationary contact members are provided with scales for facilitating the setting of the same, and the resiliently-mounted contact members are so 20 constructed as to permit effective engagement with their respective stationary members, irrespective of the setting of the same.

30 Figure 1 of the accompanying drawing is a top plan view of a thermal relay embodying my invention, and Fig. 2 is a view, partially in section, and partially in elevation, of the relay shown in Fig. 1.

A thermal relay 1 comprises, in general, 35 a helical bimetallic spring 2, a main movable member 3, contact members 4 disposed thereon, and adjustable stationary contact members 5.

The lower end of the bimetallic spring 2 is connected to a supporting yoke 5 that is 40 secured to members 6 which are supported by posts 7. The upper end of the spring 2 is secured to a spindle 8 which, in turn, is connected to the main movable member 3.

45 The main movable member 3 comprises an annular member 9 that is secured to an insulating member 10 to thus effectively insulate the same from the spring 2. The contact members 4 are mounted on the member 9 at equi-distant points around the periphery thereof, and are yieldingly held against relative movement in either direction by springs 12. A relatively light spring 13 is provided for electrically connecting the terminal clip 11 on the movable member 3 to a stationary terminal member 11^a, which

may be connected to an electric circuit (not shown). A heater 14 is disposed within the spring 2 and is provided for heating the same in accordance with any predetermined circuit conditions.

The stationary contact members 5 are mounted on lever arms 15 having pivotal points concentric with the pivotal points of the contact members 4. Thumb screws 16 are provided for adjusting the position of the lever arms 15, and scales 17 are provided for facilitating the setting of the same. The contact members 5 are insulated from the arms 15 and are electrically connected to various secondary relays (not shown).

The contact members 4 are so resiliently mounted that, irrespective of the relative positions of the various groups of lever arms 15, the contact members 4 will effectively engage their respective contact members 5. That is, the contact members 4 will turn relatively to each other upon engaging their respective contact members 5 to permit further turning movement of the main member 3 to thus effect engagement between the contact members 4 and 5 of other groups.

55 The engagement of any movable contact member 4 with a corresponding relatively stationary contact member 5 establishes a corresponding external control circuit whereby a desired operation is effected of apparatus in such circuit.

It is apparent that the operation of such apparatus may be effected in any desired sequence by reason of the relative adjustments 60 permissible between the movable contact members 4 and the stationary contact members 5. Such operations may also be effected in accordance with the direction of movement of the movable member 3 and the consequent engagement of the contact members 4 and 5 to establish the several control circuits.

70 My invention is not limited to the specific structure illustrated, as it may be variously modified without departing from the spirit and scope of the invention, as set forth in the appended claims.

I claim as my invention:

75 1. A thermal relay comprising a movable member, a bimetallic spring for actuating said movable member, means for heating said spring, a plurality of relatively movable contact members mounted on said movable member, and adjustable contact mem- 80

85 85 90 95 100 105 110

bers for co-operating with the relatively movable contact members.

2. A thermal relay comprising a pivotally mounted member, a bimetallic member for actuating the same, a plurality of relatively movable contact members mounted thereon and adjustable stationary contact members therefor.

3. A thermal relay comprising a pivotally mounted member, a bimetallic spring for actuating the same, a heating winding for the bimetallic spring, four pivotally mounted contact members mounted at equidistant points on the pivotally-mounted member and a plurality of adjustable contact members for co-operating with the pivotally mounted contact members.

4. A thermal relay comprising a pivotally mounted main member, a bimetallic spring for actuating the same, a plurality of relatively-movable contact members pivotally mounted on the main member, adjustable contact members, and means for yieldingly holding the pivotally mounted contact members in predetermined positions relative to the main member.

5. A thermal relay comprising a pivotally mounted main member, a bimetallic spring for actuating the same, a plurality of contact members pivotally mounted at equidistant points on the periphery of the main member, pivotally mounted adjustable contact members for each of the movable contact members, and means for permitting the movable contact members to so slidingly engage the adjustable contact members that effective engagement is obtained, irrespective of the positioning of the adjustable contact members.

6. A thermal relay comprising a base

member, a main movable member, a helical bimetallic spring connected between the base member and the main movable member, a heater disposed within the bimetallic spring, resiliently mounted contact members on the main movable member, adjustable contact members therefor, and scales for the adjustable contact members.

7. A thermal relay comprising a thermally responsive actuating member, a plurality of contact members actuated thereby and a plurality of adjustable contact members relatively stationary with respect to the actuated contact members and means whereby the adjustable contact members may be arranged to permit engagement thereof by the actuated contact members in any predetermined sequence.

8. A relay comprising a movable member actuated in accordance with external conditions, a plurality of sets of relatively adjustable and stationary contact members, a plurality of contact members actuatable by the actuated member to severally engage the corresponding stationary contact members.

9. A relay comprising a movable member actuatable in accordance with a condition to be controlled, a plurality of contact members controlled thereby, a plurality of relatively stationary contact members adjustable to permit engagement thereof by the movable contact members in a predetermined sequence and means for maintaining the first engagement effected while a subsequent engagement is being effected.

In testimony whereof, I have hereunto subscribed my name this 17th day of Dec. 1918.

ORA A. COLBY.
